RACK FOR HOSIERY

Vernon F. Blomquist, Portland, Oreg.

Application July 1, 1948, Serial No. 147,322

Term of patent 14 years

(Cl. D33—8)

To all whom it may concern:

Be it known that I, Vernon F. Blomquist, a citizen of the United States of America, residing at Portland, in the county of Multnomah and State of Oregon, have invented a new, original, and ornamental Design for Racks for Hosiery, of which the following is a specification, reference being had to the accompanying drawing, forming part thereof.

In the drawing:

Fig. 1 is a perspective view of the rack for hosiery, showing my new design;

Fig. 2 is a front elevational view; and

Fig. 3 is an end elevational view, looking from either end of the rack for hosiery.

I claim:

The ornamental design for a rack for hosiery, as shown.

VERNON F. BLOMQUIST.
